(57) **CLAIM**

The ornamental design for a sight glass applied in refrigeration system, substantially as shown and described.

DESCRIPTION

FIG. 1 is a front view of a sight glass applied in refrigeration system comprising a new, original and ornamental design;

FIG. 2 is a rear view of a sight glass applied in refrigeration system comprising the new, original and ornamental design;

FIG. 3 is a left-hand side view of a sight glass applied in refrigeration system comprising the new, original and ornamental design;

FIG. 4 is a right-hand side view of a sight glass applied in refrigeration system comprising the new, original and ornamental design;

FIG. 5 is a top view of a sight glass applied in refrigeration system comprising the new, original and ornamental design;

FIG. 6 is a bottom view of a sight glass applied in refrigeration system comprising the new, original and ornamental design; and,

FIG. 7 is a perspective view of a sight glass applied in refrigeration system comprising the new, original and ornamental design.
